UNITED STATES PATENT OFFICE.

FRANK B. FOSTER, OF BEAVER, PENNSYLVANIA.

METHOD FOR MAKING METAL CASTINGS.

Application filed May 3, 1924. Serial No. 710,771.

My invention relates to methods for making metal castings, and more particularly to the production of rolls with chilled iron wearing surfaces.

5 One object of the present invention is to provide a method involving in its preferred adaptation a simple and efficient centrifugal casting machine which will make rolls solid from a combination of metals, particularly 10 iron and steel, or alloys of either or both of them. To obtain a smooth finish in the hot rolling of metals, particularly iron and steel, iron rolls with chilled surfaces are preferably used. The greatest defect of 15 such rolls now in use is their comparatively low strength. It is one of my objects to produce a method for producing rolls of superior strength, and hardness of wearing surface. Other objects appear hereinafter.

20 Referring to the accompanying drawings, Fig. 1 is a central longitudinal section of the preferred form of my casting machine in its horizontal position, parts being in side elevation; Fig. 2, an end view of Fig. 1; Fig. 3, a horizontal section of Fig. 1 on the line III—III; Fig. 4, a side elevation of 25 my machine in its vertical position, a portion having been broken away; Fig. 5 is a side elevation of the outer end of my casting apparatus showing a modification; Fig. 6, a similar view but showing the apparatus in a vertical position; and Fig. 7, a sectional detail showing the slidable connection of the 30 stand 29 with its support.

35 On the drawings 1 designates standards or supports on which are mounted the bearings 2 for the trunnions 3 of the cradle 4, the trunnions being horizontal and connected to the opposite sides of the cradle 40 intermediate of its ends, so that the cradle may assume horizontal and vertical positions. For moving the cradle from one position to another on its trunnions, I extend one of the trunnions beyond its bearing 2 and provide the extension with the worm-wheel 5, which is operated by the worm 6.

50 The cradle is shown as a hollow cylinder with two external annular hollow ribs or housings 7 opening into the hollow of the cylinder. These housings contain each a

series of rollers 8 supported in the radially movable bearing blocks or slides 9 guided by the internal side walls of the housings 7 and by the rods 10 which are parallel with 55 the cradle axis and have their ends extending through the opposing faces of the ribs 7 and through the blocks 9 and the rollers therein. Each rod thus forms the axle for two opposite rollers in the two ribs. The 60 opposing faces of the ribs have radial slots 11 for the rods 10 so that the latter may have free radial movement to a certain extent. On the peripheral walls of the ribs 7 are the outwardly-extending projections 14 which contain the compressed springs 12 bearing on the outer ends of the blocks 9. Screws 13 threaded in the outer ends of the 65 projections 14 serve to adjust the pressure which the springs exert on the rollers 8, the 70 latter bearing upon the annular ribs or riding rings 15 on the periphery of the rotary cylindrical metal mold body or flask 16, arranged within the cradle and concentric therewith. The lower end of the flask is 75 closed by the cap 17 which is preferably integral with the downward stem or extension 18 in axial alinement with the flask. The stem 18 has the peripheral or annular thrust bearing rib 19 arranged between two circular 80 series of thrust-bearing rollers 20 and 21 carried by the ring 22 secured in the lower end of the cradle 4. The lower end of the stem 18 is provided with the driven belt-wheel 23 connected by the belt 24 running 85 over the pulley 25 driven at the desired speed by the electric or other motor 26 attached to the lower portion of the cradle.

In the manufacture of a cast metal roll, I place in each end of the flask 16 rings 27 of 90 molding sand or the equivalent conformed in its dimensions and shape to the corresponding dimensions and shapes of the roll-necks to be cast, the space 28 between the sand-rings being left bare as a chill for 95 casting of the body of the roll against.

To supply the mold with molten materials I may provide a movable stand 29 having a horizontal opening 30 in line with the end of the mold when in horizontal position, 100 as shown in Fig. 1. The stand carries the hollow horizontal shaft 31 in alinement

with the said opening and has at its outer end the worm-wheel 32 having an opening in line with the hollow of the shaft 31. To the outer face of the wheel 32 is attached 5 the plate or casting 33 which supports three ladles, 34, 35 and 36, arranged to discharge their contents into the tube 37 which is supported by the plate 33 and projects into the space 28. The wheel 32 is rotated by the 10 worm 37. The ladles have their bodies considerably eccentric of their discharge nozzles 38 and their filling openings 39 on the sides opposite their deepest portions. This structure allows each ladle to come to a position 15 with its filling opening up as is the case with the ladle 34. In this position molten metal or other material may be deposited therein. Upon rotation of the wheel 32 the ladle 34 rises so as to discharge its contents, 20 as cast-iron, into the tube 37 while the ladle 35 rises to its filling position. In a similar manner the ladle 35 containing steel, for example, is discharged and the ladle 36 brought to filling position, if required. Materials 25 may be supplied to the mold in other ways.

With the parts as shown in Figs. 1, 2 and 3, the motor 26 is started and caused to rotate the flask 16 at the desired speed. Molten cast-iron of the desired composition is introduced into the space 28 through the tube 37 or other suitable feeder. The rotation of the mold causes the iron to be forced radially outwardly so as to form a 35 coat 38 on the inner face of the flask or mold surface in the space 28. Molten cast-iron is supplied to the space 28 until the desired thickness has been deposited on the inner face of the mold. Then steel of the desired composition is supplied to the space 28, the cradle 4 being swung to vertical position when the iron in the mold has become sufficiently hard or solid to retain its shape and position. Molten steel is supplied by 40 any suitable means until the mold is entirely filled as shown in Fig. 4. After cast iron has been introduced into the space 28, a suitable mixture of hot metal may be introduced to form a perfect amalgamation between the cast iron and the steel or alloy of steel which forms the core or shaft of the casting. I do not limit the process so as to require the mold to be swung to its vertical position just when the desired 50 depth of cast-iron has been cast or solidified against the mold wall; it should be swung to vertical position prior to the filling of a complete cross-section of the mold.

The metal mold surface in the space 28 55 imparts a chilled surface to the roll. This surface can be modified as to depth and other characteristics in obvious ways. I may cast a roll with a chilled iron face and a steel shaft or core, as described; or a roll 60 with a high carbon and high chromium

face and low carbon steel core or shaft; or a roll consisting of only one kind of metal, in which case the roll will be homogeneous and perfect to an extent which cannot be attained with any other method of casting 70 known to me. When a buyer gets an iron roll with a soft chill, he is after the strongest chilled roll he can get. When he buys a roll with a harder chill he makes a sacrifice of roll strength to get the hardness or 75 wearing quality he desires. With my method it is possible to make all rolls with wearing surfaces having the hardest grade of chill, and at the same time produce rolls 80 from two to three times stronger than would 85 be possible with all-iron rolls.

Referring now to Figs. 5, 6, and 7, the bracket 40 is carried by the lower side of the cradle 4 and at its outer end. The bracket extends downwardly for a short distance and then outwardly parallel with the cradle. The stand 29 is slidable on the upper surface of the outer portion of the bracket and is held and guided thereon by the dovetailed grooves 41 in the stand fitting the correspondingly-shaped ribs 42 connected by screws to the bracket, the ribs and grooves being parallel with the cradle. 90

A pair of toggle links 43 and 44 are pivoted together by the pin 45, the extreme 95 ends of the links being pivoted to the cradle 4 and the stand 29 by the pins 46 and 47, respectively. When the apparatus is horizontal, as shown in Fig. 5, the stand 29 is at its left-hand position and the links 43 and 44 are flexed upwardly. When the cradle is brought to its vertical position, shown in Fig. 6, the interconnected ends of the links opposite the pin 45 engage the stop 48, thereby causing the toggle links to be straightened out, as shown in Fig. 6. This causes the stand 29 and the connected parts to move outwardly away from the cradle so that the discharge end of the tube 37 will be withdrawn from the mold, thereby preventing the metal discharged through the tube as the cradle is elevated, from becoming fastened in the casting. 100 105 110

I do not limit the invention to any particular means for swinging the cradle, or for rotating the flask or for gearing the motor to the flask or for supplying the mold with material in either position or to having the mold even substantially vertical during the second part of the process, as the metal would fill the mold space when considerably inclined except at the close of the operation. 115 120

I claim—

1. The method of casting a roll with chilled working face which consists in pouring molten iron into a horizontal revolving mold having a chilling surface against which the molten iron is deposited by centrifugal force, and, after the iron so de- 125 130

2. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, pouring into the mold molten metal of a different composition from the cast iron, and moving the mold toward a vertical position while the casting is hollow.

3. The method of casting a roll with
20 chilled working face which consists in pouring
molten iron into a horizontal revolving
mold having a chilling surface against
which the molten iron is deposited by cen-
trifugal force, and, after the iron so de-
25 posited has hardened sufficiently to main-
tain the desired depth of chill in a fixed
form, pouring molten steel into the mold,
and moving the mold toward a vertical po-
sition while the casting is hollow.

30 4. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, moving the mold toward and finally to a vertical position, molten metal being fed to the mold until the casting is made solid to the desired level.

5. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, moving the mold to a vertical position, molten metal being fed to the mold until the casting is made solid to the desired level.

6. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, pouring into the mold molten metal of a different composition from the cast iron, and moving the mold toward and finally to a vertical position while the casting is hollow.

7. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, pouring into the mold molten metal of a different composition from the cast iron, and moving the mold to a vertical position while the casting is hollow. 70 75

8. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, pouring molten steel into the mold, and moving the mold toward and finally to a vertical position while the casting is hollow. 80 85

9. The method of casting a roll with chilled working face which consists in pouring molten iron into a horizontal revolving mold having a chilling surface against which the molten iron is deposited by centrifugal force, and, after the iron so deposited has hardened sufficiently to maintain the desired depth of chill in a fixed form, pouring molten steel into the mold, and moving the mold to a vertical position while the casting is hollow. 90 95

10. The method of casting a roll with chilled working face which consists in pouring molten iron into a coreless horizontal revolving mold having a chilling surface against which the molten iron is deposited by centrifugal force, and, after the iron so deposited has hardened sufficiently to maintain the desired depth of chill in a fixed form, moving the mold from the horizontal position and simultaneously feeding molten metal to the mold until the casting is made solid to the desired level. 100 105 110

120
125
130

12. The method of casting a composite metal roll which consists in casting molten metal of one characteristic by centrifugal action against the interior surface of a coreless hollow rotating horizontal mold to obtain predetermined thickness of cast metal and then moving the mold from the horizontal position and supplying the interior of the casting with molten metal of a different characteristic to the desired quantity.

13. The method of casting a composite metal roll which consists in casting molten metal of one characteristic by centrifugal action against the interior surface of a low rotating horizontal mold until a predetermined thickness of metal has been so cast, and then moving the mold from the

horizontal position and simultaneously supplying the interior of the casting with molten metal of a different characteristic to the desired level.

In testimony whereof, I hereunto affix my signature this 24th day of April, 1924.

FRANK B. FOSTER.
